UNITED STATES PATENT OFFICE.

HOWARD C. NOBLE, OF NEW BRITAIN, CONNECTICUT.

DESIGN FOR A CLASP-BUCKLE.

SPECIFICATION forming part of Design No. 19,448, dated November 26, 1889.

Application filed July 31, 1889. Serial No. 319,343. Term of patent 7 years.

To all whom it may concern:

Be it known that I, HOWARD C. NOBLE, of New Britain, in the county of Hartford and State of Connecticut, have produced a new and original Design for a Clasp-Buckle; and the following is declared to be a full, clear, and concise description thereof, reference being had to the accompanying drawing.

My design relates to clasp-buckles.

10 The design embraces elongated loops *a a* for receiving the ends of the belt, and between the loops, attached to the side thereof at about the middle, is a circular frame *b*, within which

frame is the representation of two lawn-tennis bats crossed and with a ball placed at 15 the center of the crossing. The said figure of a ball and bats crossed is attached to the surrounding frame at two or more points, producing an open-work effect.

What I claim as new is—

20 The design for a clasp-buckle, as shown and described.

HOWARD C. NOBLE.
